UNITED STATES PATENT OFFICE

2,348,646

CONVERSION OF HYDROCARBON OILS

Edward D. Reeves, Cranford, N. J., assignor to
 Standard Oil Development Company, a corpora-
 tion of Delaware

Application July 5, 1941, Serial No. 401,281

3 Claims. (Cl. 196—52)

This invention is directed to the conversion of hydrocarbon oils and constitutes a continuation-in-part of my earlier application Serial No. 256,630, filed February 16, 1939, entitled "Conversion of hydrocarbon oils."

In the above-named application I have disclosed an integrated, unitary process for the conversion of crude oils into gasolines wherein the crude is initially segregated into a plurality of separate fractions and each fraction then subjected to independent conversion treatments in the presence of finely-divided catalysts under conditions selected for the production of maximum yield of gasoline having high anti-knock properties.

The present invention is directed to the combination of catalytic conversion and fractionation of conversion products to segregate the desired constituents therefrom.

In the past it has been the general practice to first separate the powder or finely-divided catalyst from the conversion products and then to pass the products directly to a fractionating tower wherein they are subjected to fractionation to segregate the desired fraction.

I have found that an overall improvement can be realized particularly in low pressure conversion processes in which substantial amounts of steam are employed in the operation by initially condensing all of the overhead products from the conversion process except for the non-condensable gases formed during the operation, then separating the water condensate phase from the oil condensate before subjecting the latter to fractionation. It has been found that the water phase so segregated contains the bulk of the powdered catalyst which remains entrained in the oil vapors after passing through the separating equipment, and by initially condensing the total conversion stream and separating the water and catalyst, the oil passing to the fractionating equipment will be substantially free of powdered catalyst and can be subjected to fractionation under any desired pressure.

For example, in catalytic cracking it is desirable in most cases to operate at a relatively low pressure level, such as at atmospheric or at a mild superatmospheric pressure. However, in cases where the cracked products pass directly to the fractionating equipment, the outlet pressure on the conversion unit must be at least sufficient to overcome the pressure drop through the fractionating and condensing equipment in order to avoid the use of gas compressors which are uneconomical to operate.

Furthermore, it is desirable to operate the fractionating equipment under substantial pressures in order to reduce the size of the fractionating tower for a given capacity and to utilize the cooling medium to the best advantage. The present invention finds particular application in cases where the cracked products contain substantial amounts of inert gases such as steam or other gaseous diluents employed to vaporize the oil. For example, in vapor phase cracking or viscosity breaking of heavy oils, it is necessary to add considerable amounts of steam or other gas to accomplish the vaporization. This inert gas increases the burden on the fractionating equipment.

In accordance with the present invention, the cracked or conversion products are first cooled to a temperature sufficient to condense the normally liquid constituents of the cracked products including the steam used for vaporization or for other purposes. The condensate is then allowed to separate into a water phase resulting from condensation of the steam and oil phase. The water phase, as previously pointed out, will contain the entrained powder carried over from the conversion process. This mixture of water and powdered catalyst can then be recovered by pumping directly into the cracking or conversion equipment. The oil phase is pumped into a combined distilling and fractionating tower which may be maintained under any desired pressure independent of the pressure of the cracking process in order to distill and fractionate the motor fuel or other hydrocarbon fractions therefrom.

For a more complete understanding of the invention, reference is now made to the accompanying drawing which is a diagrammatic illustration of an apparatus suitable for carrying the invention into effect.

Referring to the drawing, the reference character 10 designates a charge line through which the oil to be processed is introduced into the equipment. As illustrated, this oil is preferably a crude petroleum fraction which is to be subjected to initial distillation to segregate the lower boiling hydrocarbons therefrom.

The oil introduced through line 10 is pumped by means of pump 11 through a preheating coil or distilling coil 12 located in furnace 13 wherein the oil is subjected to a temperature which would vaporize a substantial portion of the oil passing therethrough. The outlet temperature of the vaporizing coil may be, for example, of the order of from 700° F. to 900° F.

Products from the vaporizing coil 12 pass

through transfer line 15 into a combined separating and fractionating tower 16 wherein the vapors separate from unvaporized residue and the vapors are fractionated to condense higher boiling constituents thereof. Unvaporized liquid and condensate formed in the bottom section of the tower 16 are withdrawn therefrom through line 17 and may be rejected from the system through line 18. However, this reduced crude or residual stock is preferably subjected to further treatment as hereinafter described.

A lower boiling condensate stock formed in the intermediate section of the fractionating tower 16 is collected in trap-out tray 19 and is withdrawn therefrom through line 20. This fraction may be treated according to the parent application hereinbefore referred to, or it may be subjected to treatment as hereinafter described.

A still lower boiling condensate fraction which may comprise heavy naphtha, kerosene, or the like may be collected in the upper portion of the fractionating tower 16 in trap-out tray 21 and may be withdrawn therefrom through line 22. This fraction may be treated as described in the parent application or subjected to any further treatment outside of the present invention.

Vapors remaining uncondensed in the fractionating tower 16 pass overhead through line 22 to a condenser 23 wherein they are cooled further to condense normally liquid hydrocarbons. Products from the condenser 23 pass to a receiver 24 wherein the liquid condensate formed in condenser 23 separates from any normal gases liberated during the distilling process. The liquid distillate is withdrawn from receiver 24 through line 25 and may be further treated as described in the parent application. Gases segregated in the receiver 24 may be removed therefrom through line 26.

Returning to the fractionating tower 16, the residual fraction withdrawn through line 17 or the gas oil fraction withdrawn through line 20, or a mixture thereof, may be passed through line 27 to a preheating and vaporizing coil 28. The oil during its passage through the vaporizing coil 28 is subjected to further heating to vaporize an additional fraction of said oil. To assist in the vaporization, water or steam is introduced through line 29 or to other points in the vaporizing coil. The amount of steam so introduced may range, for example, from 5 mol per cent to 50 or more mol per cent, depending upon the character of the oil to be vaporized.

The heated oil after passing through the vaporizing coil 28 passes through transfer line 31 to a separator 32 wherein vapors formed in the heating coil 28 are segregated from any unvaporized residue. If desired, additional steam for assisting in the separation may be introduced into the separator through line 33. Liquid residue separated in the separator 32 is withdrawn therefrom through line 34.

Vapors liberated in the separator 32 pass overhead through line 35 to a dispersion chamber 36 in which they are admixed with powdered contact material introduced into the dispersion chamber 36 through line 37. This powdered contact material may be any cracking catalyst such as activated clays, synthetic gels of silica and alumina or silica having other cracking catalysts combined therewith. The amount of powdered catalyst introduced into the vapors in the dispersion chamber 36 may vary over an extended range, depending upon a number of factors, such as the activity of the catalyst, composition of

the feed, temperature of the cracking operation, and per cent conversion desired. In general, this amount will be between 0.5 and 10 parts of catalyst per part of oil by weight. The temperature of the oil vapors introduced into the dispersion chamber 36 may be of the order of from 700° F. to 950° F.

The dispersion of oil vapors and powdered catalyst formed in the dispersion chamber 36 passes through line 38 to a cracking or reaction zone 39 wherein the oil vapors are retained for a period sufficient to obtain the desired conversion into motor fuel. For illustrative purposes, the reaction zone has been shown in the form of a vertical tower through which the dispersion passes in an upward direction. When employing this type of reaction chamber, the velocity of the oil vapors may be regulated so that the time of residence of the catalyst within the tower may be materially longer than the time of residence of the oil vapors.

It will be understood, however, that the present invention is not restricted to the particular type of reactor illustrated, since other types of cracking chambers, such as coils, horizontal drums and the like, may be employed in lieu thereof.

The cracked products and catalyst after passing through the cracking zone 39 are transferred through line 41 to a separator such as a cyclone separator 42 for separation of the powdered catalyst from the cracked vapors. The powdered catalyst separated from the cracked vapors in the cyclone separator 42 discharges into a vertical column 43 into which is introduced an inert stripping gas through line 44. If desired, the column 43 may be provided with suitable baffles for intermixing the stripping gas with the catalyst. The catalyst after passing through the column 43 discharges into a hopper 45.

Cracked vapors after being treated to separate the powdered catalyst therefrom are removed from the cyclone separator 42 through line 46.

In accordance with the present invention, these cracked vapors are passed to a condenser 47 wherein they are cooled to a temperature sufficient to condense all the normally liquid constituents present in the product. While an indirect heat exchanger 47 has been shown for effecting this cooling, it will be understood that other types of cooling devices, such as a spray chamber for effecting direct contact between the cracked vapors and cooling agent, may be employed in lieu thereof. Products from the cooler 47 pass through line 48 to a receiver 49 wherein liquid formed in the cooler 47 separates from uncondensed gases. Furthermore, the water condensate formed by condensation of the steam used in the process and containing any entrained catalyst carried over from the separator 42 will collect as a bottom layer in the separator 49 and may be withdrawn therefrom through line 50 and returned by means of a suitable pump to the inlet side of the preheating coil 28 and there combined with fresh oil for the process.

Gases separated from the liquid condensate in the receiver 49 are withdrawn therefrom through line 51 and may be subjected to further treatment for the recovery of gasoline constituents therefrom. The line 51 may be provided with suitable release valves 52 for maintaining the desired pressure on the cracking system. In accordance with the present invention, the cracking system is operated at relatively low pressure. For example, the inlet pressure on the oil vapors passing to the cracking zone may be only suffi-

cient to overcome the pressure drop through the cracking and separating equipment.

The liquid oil comprising gasoline and higher boiling fractions collected in receiver 49 is withdrawn therefrom through line 53 and is forced by means of pump 54 to a heating coil 55 wherein the oil is heated to a temperature sufficient to distill the lower boiling motor fuel constituents therefrom. Products from the heater 55 then pass to a combined distilling and fractionating tower 56 wherein the oil is subjected to distillation and fractionation to separate the same into the desired fractions. Such fractionation may consist, for example, in the distillation or liberation of motor fuel from the higher boiling constituents. If desired, additional heat may be added to the fractionating tower 56 through heating coil 57. Vapors liberated in the distilling and fractionating tower 56 pass overhead through line 58 to a condenser 59 wherein the normally liquid products are condensed. This product may consist, for example, of a gasoline fraction of the desired end point. Products from the condenser 59 then pass to a second receiver 61 wherein the uncondensed gases liberated during the distilling and fractionating treatment are separated from the liquid condensate. The gases so liberated are removed from receiver 61 through line 62 having a release valve 63 for imposing the desired pressure on the fractionating system. For example, the fractionating tower 56 may be operated under a substantial superatmospheric pressure, such as from 100 to 500 pounds per square inch. The gasoline or naphtha formed in the process collects in receiver 61 and is withdrawn from the bottom thereof through line 64 from which it may be passed to other purifying and refining treatment outside the scope of the present invention.

Returning to the catalyst hopper 45 receiving the catalyst separated from the cracked vapors, the catalyst collected therein may be discharged through line 65 having a suitable feeding device such as a valve 66 from which it may be fed at a controlled rate into a dispersion chamber 67 into which a regenerating or carrier gas may be introduced through line 68. The catalyst-gas dispersion formed in the dispersion chamber 67 is transferred through line 69 to a regenerating chamber 71 wherein the catalyst is subjected to regenerative treatment for removal of carbonaceous deposits formed during the cracking operation. This regenerative treatment may be used by maintaining an oxidizing atmosphere in the regenerating chamber 71. To this end, the carrier gas introduced through line 68 may consist of air or a mixture of air and inert diluent gases, or it may consist of an inert diluent gas and the air or other oxidizing gas may be separately introduced into the regenerating chamber. For illustrative purposes, the regenerating chamber 71 is also shown in the form of a vertical tower through which the dispersion passes in an upward direction. It will be understood, however, that the invention is not restricted to the particular type of regenerating chamber employed for this purpose. The velocity of the carrier gas passing through the regenerator 71 may be regulated so as to maintain the catalyst within the regenerating chamber for a period sufficient to remove at least the major portion of the carbonaceous deposits contained on the catalyst material. The dispersion of regenerating gas and regenerated catalyst after passing through the regenerating chamber 71 passes through line 78 to a cyclone

separator 79 or other equivalent device for separation of the regenerated catalyst from the regenerating gas. The regenerating gas after passing through the cyclone separator or other suitable separating and purifying device may be rejected from the system through line 81. The regenerated catalyst separated in the separator 79 discharges into a vertical column 82 into which an inert stripping gas may be added through line 83 for removing any absorbed oxygen retained in the catalyst. The regenerated catalyst discharges from column 82 into a catalyst hopper 84 from which it is fed by means of a suitable feeding device such as a worm screw 85 into a mixing chamber 86 in which it is admixed with a gaseous carrier introduced through line 87. This gaseous carrier is preferably a non-hydrocarbon gas such as steam, nitrogen, hydrogen, or the like. The dispersion or mixture of gas and regenerated catalyst discharges from a chamber 86 through line 37 into the initial dispersion chamber 36 where it again admixes with oil vapors to be cracked.

It will be understood that makeup catalyst may be introduced at any desired point in the system for maintaining the desired amount of catalyst in circulation.

Having described the preferred embodiment of the invention, it will be understood that it embraces such other variations and modifications as come within the spirit and scope thereof.

What is desired to be protected by Letters Patent is:

1. In a process for converting higher boiling hydrocarbons into lower boiling hydrocarbons suitable for motor fuel wherein a substantial volume of steam is employed to vaporize the oil to be cracked; the improvement which comprises passing oil vapors and steam through a cracking zone in admixture with a powdered cracking catalyst, maintaining said cracking zone at cracking temperature, thereafter separating the catalyst from the cracked products, cooling the total cracked products to a temperature sufficient to liquefy all normally liquid hydrocarbon constituents and steam, separating the steam condensate containing powdered catalyst from the oil condensate, returning said steam condensate to the cracking zone, and distilling and fractionating said last-named condensate under a pressure materially above the pressure maintained in the cracking zone to separate the desired motor fuel fraction therefrom.

2. In a process for converting higher boiling hydrocarbons into lower boiling hydrocarbons suitable for motor fuel wherein a substantial volume of steam is employed to vaporize the oil; the improvement which comprises passing the oil vapors and steam through a cracking zone in admixture with a powdered cracking catalyst, maintaining said cracking zone at active cracking temperature, thereafter separating the catalyst from the cracked products, cooling the total cracked products to a temperature sufficient to liquefy all of the normally liquid constituents and steam, separating the steam condensate containing powdered catalyst from the oil condensate, returning said steam condensate to the cracking zone and distilling and fractionating the last-named condensate to separate a desired motor fuel fraction therefrom.

3. A method of cracking hydrocarbon oils which comprises vaporizing the oil to be cracked in the presence of a substantial amount of steam, forming a mixture of oil vapors, steam, and pow-

dered cracking catalyst, transferring said mixture through a cracking zone maintained at cracking temperature and at substantially atmospheric pressure except for the necessary pressure to overcome the pressure drop through the cracking and separating equipment, maintaining the oil vapors in admixture with the catalyst for a period sufficient to obtain a substantial cracking thereof, thereafter separating the bulk of the cracking catalyst from the vaporous conversion products and steam, thereafter cooling said vaporous conversion products and

steam to a temperature sufficient to condense all normally liquid hydrocarbon constituents and steam, separating the oil condensate substantially free of entrained catalyst from the steam condensate containing a substantial portion of entrained catalyst, distilling and fractionating the oil condensate to separate a desired motor fuel fraction therefrom, and returning the water condensate containing said catalyst to the cracking process.

EDWARD D. REEVES.
